UNITED STATES PATENT OFFICE.

HENRY E. RESTER AND GEORGE BOYLE WERCKLEY, OF BOGALUSA, LOUISIANA.

LOCOMOTIVE RAILWAY ATTACHMENT FOR TRACTORS.

Application filed February 23, 1926. Serial No. 90,183.

The present invention pertains to locomotives of the internal combustion type, wherein a tractor is utilized as the power plant thereof; and relates more particularly to an improved under-truck upon which the tractor may be mounted.

The object of the present invention is to produce a sub-truck attachment for the tractors to convert the latter into a locomotive particularly useful in handling cars at lumber mills, brick yards, mines, dirt cars and for similar purposes, said truck having features of novel constructions producing a durable and rugged, yet flexible, structure simple and efficient, and in manufacture comparatively more economical, and specifically adapting the tractor thereto for more convenient and ready attachment and detachment.

It is also an object of the invention to provide an under-frame or truck constructed to support a tractor in such a manner as to permit as short a wheel base as desired and having means permitting the wheel base thereof to be varied by an easy adjustment or relocation of one axle on the truck without change in the driving connection thereof and without requiring addition or substitution of parts of the driving connection or an adjustment thereof.

Another object of the invention is the provision of means for protecting the power plant and its operator from injury by the load on the cars, to which the locomotive is attached, moving or shifting forwardly or rearwardly.

With these and other objects in view, the invention resides in sundry details of construction, combination and arrangements of parts whereinafter are more fully described and pointed out in the appending claims.

In this specification and the annexed drawings, the invention is disclosed in the form on which it is considered to be the best, but the invention is not limited to such form because it is capable of being embodied in other forms; and it is to be understood that in and by the claims following the description herein, it is intended to cover the invention in whatever form it may be within the scope thereof.

In the drawing, which shows the preferred

embodiment of the invention as at present devised:

Figure 1 is a side elevation of a locomotive constructed in accordance with the present invention;

Figure 2 is a plan view of the locomotive as shown in Figure 1;

Figure 3 is a plan view of the underframe or railway truck with the tractor or power plant removed;

Figure 4 is a longitudinal section of truck taken substantially on line 4-4, Figure 3;

Figure 5 is a transverse section of view of the locomotive taken substantially on line 5-5 of Figure 2 and looking in the direction of the arrows;

Figure 6 is a fragmental side elevation of the truck underframe, with tractor wheel removed, illustrating the driving connection between the driving axle of the tractor and the truck axle;

Figure 7 is a side elevation of the inner side of the car guard, shown in Figure 6.

Figure 8 is a side elevation of an extensible connecting rod;

Figure 9 is a vertical section taken on line 9-9 of Figure 8; and

Figure 10 is a fragmentary longitudinal sectional view taken through the truck-frame and showing the lower portion of the tractor support in position thereon.

Throughout the specification and drawings like characters of reference denote like and corresponding parts of the device.

In constructing a locomotive in accordance with the present invention, a tractor with its transmission mechanism and driving shaft and axles is employed and it is the purpose of this invention to utilize a tractor commercially known as "Fordson", but it should be understood that the invention is not limited to the use of "Fordson" tractors.

The truck-frame, upon which the tractor is mounted, is specifically designed so that the changes necessary in the parts of the tractor for its use on the truck-frame are greatly reduced compared with those of the same type which have been previously designed, used or proposed.

In the preferred form of the invention, which is now in practical use, the following

are briefly the changes which are made in the tractor:—All four wheels and the front axle are removed which is necessary in all events, and, for more effective use as a locomotive on a railroad, the differential has interposed between its gears a blind-spider to which the gears are connected by which connection both halves of the rear axle will operate as one shaft. Also, the gears in the transmission may be rearranged so as to reverse the rotation of the rear axle to that of its normal rotation for a purpose to later appear, and which adjustment is well known in connection of "Fordson" tractors. The steering mechanism associated with a front axle is unnecessary for steering proposed when the locomotive of this invention is designed to run on tracks, but the steering column and drag-links thereof are connected through suitable means to brakes on the front traction wheels of the locomotive truck.

In the drawings T denotes the outline of the tractor which includes the engine E, the radiator R, the gasoline tank G, the differential casing C, and the rear driving axle housing 14, connected to the casing C in the usual manner as shown. All these parts may be of standard type of construction found in tractors commercially sold and are applied without change in the locomotive, except as stated above.

The tractor, with its wheels and the front axle removed, is to be mounted on the sub-truck F. This sub-truck comprises a frame having a pair of spaced and elongated members 10 connected at their ends by transverse end members 11. These side and end members are formed from sheet steel or other suitable metals, and are of considerable width and arranged vertically on the edge. The end portions 13 of the members 11 are extended at right angles thereof and engage the inner faces of said side members 10 at their ends, where they are suitably secured together, such as by bolt 12. The side members 10, as before stated, are of considerable width and are formed with slots or cut-out portions, 14, 15, and 16 arranged at spaced intervals and extend from the lower edge thereof for distances upwardly of the members to receive journal boxes 17 and 17' in which transverse axles 18 and 19 are mounted.

This construction of the frame F with its side members 10 and end members 11 of relatively wide elongated strips or plates provide the frame with the necessary strength and weight but possessing greater flexibility than the other types of frame constructions which have been previously used or proposed in connection with devices of the present type. The flexibility absorbs or takes-up a greater part of the strain in rounding curves and the like in-

cluding the torque strain, which is otherwise transmitted to the tractor. Portions of the side members 10 are cut-out as indicated at x, y and z to increase their flexibility and to permit access to the various parts of the device.

The outer ends of the axles project beyond the frame and have mounted thereon front and rear traction wheels 20 and 21, respectively. Opposite the edges of the notches or slots 14, 15 and 16 are provided guides 9 which extend into corresponding vertical grooves in the journal boxes 17 and 17' as can be clearly seen on Figure 4, thus permitting the journal boxes to be slidably moved into and out of said guide-slots and maintaining them securely on the frame. The lower end of each of the guide-slots 14, 15 and 16 is closed by a retaining plate 22 held in position by suitable bolts 23.

The journal box slots 14, which are in front end of the truck-frame F, are of greater length than the journal box slots 15 and 16. Interposing between the top face of the front journal boxes 17 and upper ends of the slots 14 are coil springs 24 for cushioning the front end of the truck frame and permitting the journal boxes 17 to yieldingly slide in the slots 14, thereby the axle 18 will rock freely in a vertical transverse plane to accommodate itself to track inequalities. The upper end of the springs are maintained in position by a stud 25 projecting thereinto, while their lower ends may be secured to the journal box 17, or the latter may have an up-standing stud thereon similar to the stud 25. It will be observed that the journal-box slots 15 and 16 are only of a size to receive the journal boxes 17' without allowing for a vertical sliding movement of the box therein.

The frame is braced transversely by horizontal plates 26 extending between the lateral portions of the end members as shown, and, in addition to providing suitable braces, serve as platforms at the end portions of the frame. Plates 26 may be independent of the end members 11 having flanges secured by the bolts to the end members, or cast integral therewith as shown.

At the forward end of the truck, preferably, between the end members 11 and the axle 18, is a transverse brace 28 having its end portions secured by bolts 29 or the like to the opposite side members 10. This brace is, preferably, a vertically arranged plate of sheet metal having flanged ends through which the bolts 29 extend, and is specifically designed to provide a supporting cradle for the forward end of the tractor by having its upper edge cut away on a suitable arc, as at 30, to accommodate the structure of the tractor body. Located on the underside of the engine crank case E, of a "Fordson" tractor, and near the forward

end thereof, is a pair of the pending perforated lugs 31, which, when the tractor is used as such, to receive a trunnion pin 31' connecting the front axle therewith. When mounted on the frame F, these perforated lugs 31 straddle the cradle 28 provided with a suitable opening 28' to register with the perforations in the lugs 31 to receive the securing trunnion pin 31'.

10 The rear end portion of the tractor is supported on the truck-frame by supporting brackets 32 disposed at the rear end portion of the frame, one of said brackets being secured to each side member 10. The brackets 15 32, of course, disposed in traverse alignment and, preferably, are formed from a metal plate having its upper end extending above the upper edge of the side members 10 and provided with suitable pockets or 20 arcuate notches 33 in which is to rest the end portions of the rear axle housing H of the tractor. As shown in the drawings, these brackets are detachably secured to the inner side faces of the side members 10 by 25 means of bolts 24 extending through the side members and the body of the plate forming the bracket. The lower edge of the bracket plates are extended at an angle to form the inwardly extending flanges 35 having 30 openings 36 therein through which the free ends of the U-shaped bolts 37 extend. The U-bolts 37 extend over the axle housing H and co-operate with the recess 33 of the supporting bracket 32 to firmly clamp 35 the rear end of the tractor to the truck frame, suitable nuts or other fastening means 38 engaging on the ends of the U-bolts, 37.

On the outer ends of the rear axle 39 of 40 the tractor are removably secured by nuts 39' gear wheels 40 and 41 respectively which mesh with the gear wheels 42 and 43 concentric with the rear truck axle 19 and, 45 preferably, made fast to rotate the traction wheels 21 thereof by being bolted directly to the inner side face of the said traction wheels by means of bolts 44. The ratio between the gears 40 and 42 and the gears 41 and 43 is such as will increase the driving 50 power of tractor or power-plant T but it is to be understood the ratio of these gears may be varied to effect a low speed with high pulling power or a high speed with a reduced pulling power to meet the 55 exigencies or demands which the locomotive may be called upon to meet.

The construction of the truck frame, with the motor supporting parts 28 and 33 disposed as shown in the drawings supporting 60 the tractor above the truck axles, permits the axles 18 and 19 to be positioned relatively close to each other between the front and rear point of support for the tractor to provide a truck with a relatively short 65 wheel base, which is of great advantage

in locomotives of the present type operating in a limited area such as lumber-yards, mines, mills, factories, stone-yards and the like, where it is necessary to round short curves and to switch cars over short 70 cross-overs, up and down abrupt and sudden inclines. This construction likewise enables easy access to the tractor permitting the quick and economical greasing, lubricating or repairing of the said tractor, from above 75 or beneath, if the same should be necessary, without dismantling the same from the truck frame.

It will be observed that the journal-box slots 15 and 16, for interchangeably receiving the journal boxes 17' of the rear axle 19 of the locomotive truck, are arranged, respectively, on opposite sides of the axle housing supporting brackets 32 at equal distances with respect to the axial center of the 80 rear axle housing retaining pockets or recesses 33, thus permitting the wheel base of the locomotive truck to be readily increased, at will, by merely removing the journal-boxes 17' from the journal-box slots 15 and 90 90 mounting the same in the journal box slots 16, without requiring any adjustment, addition or substitution of parts of the driving connection between the traction wheels 21 and the rear axle 39 of the tractor mounted in the supporting brackets 32, as the gears 40, 41, 42 and 43 will properly interengage 95 when the journal boxes 18 are properly secured in the slots 16.

The driving power or traction of the present locomotive may be, and preferably is, increased by connecting the rear drive wheels 21 with the front wheels 20 of the truck frame by suitable connecting rods 45, as is customary in locomotive practice, the 100 wheels being properly weighted, as at 46, at points diametrically opposite the points of connection 47 of the rods 45 with said wheels 20 and 21. As shown in the drawings, the wheels 20 and 21 are arranged to 105 provide a short wheel base, but, when the rear axle 19 of the truck-frame is positioned in the journal-box slots 16 to provide longer wheel base, it will be necessary to change the connecting rods 45 for one of greater 110 length. However, it is preferred to provide an adjustable connecting rod 45', as shown in Fig. 8, in order that no change will be necessary. The adjustable rods 45', comprising extensible sections r and s and the 115 adjustment effected through the bolts 48.

In order to protect the power plant and the operator from the load on the cars shifting either forwardly or backwardly on to the locomotive, by reason of sudden jerks or stops or the like, upwardly extending shields 49 are provided, respectively, at each end of the truck-frame F. These shields are of heavy gauge steel plates of a width substantially coincident with the length of the end 125 130

members 11 to which latter the shields are detachably affixed by means of bolts or other suitable fasteners 50. The shields extend upwardly for a distance to properly perform the functions for which they are designed, and at least extend higher than the motor. The shields 49 preferably extend around the sides of the car for a slight distance, as shown in the drawings, and are constructed on a transverse curve which increases their rigidity; and they are provided with a plurality of perforations 51 permitting the passage of air to pass therethrough for cooling the motor and also reducing the resistance of the air or wind pressure against the shields, when moving at relatively high speed.

A draw head or coupling 52 is provided at each end of the truck and may be of any desired or approved type, being secured to the end members 11 of the truck-frame.

The wheels 40, 41, 42 and 43 are inclosed by suitable guards 53 encasing all exposed portions of the gears. The guards 53 are each preferably made of two sections *h* and *i*, the top section *h* comprising two spaced side walls connected by an arcuate end wall, the lower section *i* being only an arcuate wall in complement of the arcuate wall of section *h*, to extend around the peripheries of the gears as shown. The walls of the top section *h* have cut-out portions *j* therein to fit around the axle housing *H*. The entire guard is held in position by bolts *k* extending through openings *k'* in the guard and secured in the side members 10 of the truck-frame. When the wheel-base of the truck is increased by shifting the journal boxes of the axle 19 in the journal-box slots 16, the guards on each side may be interchanged from one side to the other in order to properly position them on the frame, as is indicated by the position of the guard shown in Figure 7.

The motor of the tractor is started by a crank handle as is usual, but this crank handle 55 is transposed on one side of the locomotive and is connected to a short transverse shaft 56 mounted in suitable bearing brackets 57 on the front platform 26. The inner end of the shaft 56 has a bevel gear 58 thereon meshing with a bevel gear 59 provided on the forwardly extending arm or extension secured to the crank shaft 60 of the tractor. The forward extension of the crank shaft 60 is held rigid in position by a suitable bracket 61 also mounted on the front platform 26.

The controller of the locomotive is the same as that of the tractor normally, the transmission being controlled through the usual shifting lever 62, and the clutch through the pedal 63, which has added thereto, in order to also permit manual operation of the clutch, the handle lever 64.

In some instances it is found necessary to

provide a braking means for the locomotive, and this is provided by mounting concentrically on the inner faces of the front-truck traction wheels 20 suitable brake drums 65, secured to the wheel by bolts 65' and having ordinary contraction brake bands 66 mounted thereon to co-operate therewith. The brake bands 66 and their operating linkage 67 and 71 are of conventional construction, the brake band on the left hand side of the locomotive being connected through the linkage of 67 to the drag link 68, which is part of the ordinary tractor equipment and connected with the steering mechanism 69. The usual steering wheel on the top of the steering column is, preferably, removed and has substituted therefor a lever-handle 70. The connecting rod 71, normally part of the steering gear of the tractor, is employed to connect the linkage 67 of the left brake to the linkage 72 of the brake band on the right front-wheel. It is obvious, therefore, that when the handle 70 is moved in one direction, the brakes on the front wheels 20 will be applied and when moved in a reversed direction will be released. The operator may occupy the seat 73 normally provided as part of the tractor structure.

From the above it will be apparent that a very practical locomotive truck-frame upon which tractors may be mounted is provided, the structure of the truck frame possessing great flexibility due to its characteristic design and fabrication, yet possessing the necessary strength and rigidity to insure durability. It is also manifest that the wheel base of the truck-frame may be made as short as desired when the truck-frame is originally designed for any particular purpose by reason of the manner in which the tractor is supported thereon, provision having been made, however, for this short wheel base to be increased by the user, when occasion demands, without requiring readjustment or making any change in the driving mechanism; and that the tractor is supported upon the under-frame in a very simple manner which permits quick and ready attachment and detachment without hindrance or difficulty, there being only two points of connection between the tractor and the frame, that is, at the point 28' and at the rear axle housing supporting brackets 32.

Although the invention, as stated among the principal objects sought to be accomplished and as illustrated in the drawings and as particularly described above, makes use of the "Fordson" tractor as the power plant for the locomotive railway truck of this invention and is specially designed for such use, it is intended that the invention, however, be not limited to the use of a "Fordson" tractor alone, because other similar tractors, or other like power plants may be used with the same facility and without necessi-

tating any material change in the truck-frame. It is also to be understood that the present device is not limited to use as a railway locomotive for it may be used as a 5 sub-frame for tractors used without railed-ways.

What is claimed is:—

1. A locomotive comprising a truck-frame having front and rear traction wheels, a supporting bracket at the front end of said truck-frame positioned above the axle of said front wheels and between the same and the front end of the frame, and supporting brackets at the rear end portion of the 10 truck frame positioned above the axle of said rear wheels and between the same and the rear end of said truck-frame, said supporting brackets being adapted to removably support structural parts of a tractor, and a 15 driving connection, whereby at least the wheels on one axle of said truck may be driven from the rear axle of the tractor when mounted on said truck-frame.

2. A truck-frame for converting tractors 25 into locomotives comprising a frame, supporting brackets at the front and rear portions of the frame for detachably receiving and supporting the tractor thereon, a front axle on the frame and having traction wheels thereon, a rear axle for said frame having traction wheels thereon, means on the frame positioned in advance of said rear supporting brackets for maintaining said rear axle on the frame, means on the frame 30 positioned to the rear of said rear supporting brackets for interchangeably receiving said rear axle and maintaining it on the frame, and a gear concentric with the axis of said rear axle and to rotate the same, 35 said gear being adapted to engage with a gear to be applied on the end of the rear axle of the tractor when mounted in said rear brackets, in either position of said rear axle.

45 3. A truck-frame as set forth in claim 2 characterized further by a connecting rod between the rear wheels and the front wheels on each side of said truck, said connecting rod being adjustable to allow for the interchanged positions of said rear axle.

4. A truck-frame for converting tractors 50 into locomotives comprising a frame, supporting brackets at the front and rear portions of the frame for detachably receiving and supporting a tractor thereon, a front axle and a rear axle for said frame having traction wheels thereon, said axles being journalled on the frame between said supporting brackets, and a driving connection 55 between said rear wheels of the truck-frame and the rear axle of the tractor when mounted in position on the frame.

60 5. A truck-frame for converting tractors into locomotives comprising side plate members connected at their ends by transverse

end members, the lower edges of said plate members being provided at their front and rear end portions with vertically extending slots, journal boxes for said slots, each having vertically disposed grooves in opposite 70 side walls to receive the opposite side edges of said slots, detachable means for closing the lower end of said slot and maintaining said journal boxes in position, transverse axles mounted in said journal boxes, traction 75 wheels on said axles, supporting brackets on said frame for detachably supporting a tractor thereon and a driving connection for connecting the wheels of at least one of said axles with the driving mechanism 80 of said tractor.

6. A truck-frame as set forth in claim 5 further characterized by having portions of said side plate members cut out to increase the flexibility of said frame.

7. In a sub-frame for tractors comprising side plate members connected at their ends by transverse members, the lower edge of said plate members being provided at their front and rear portions with vertically extending slots, journal boxes mounted in said slots, transverse axles mounted in said journal boxes, traction wheels on said axles, means on the frame for supporting a tractor thereon, means for establishing a driving connection between the tractor and, at least, one of the traction wheels of the frame, said journal box slots for the front axle journal boxes being of greater length than the journal boxes whereby the latter may reciprocate in said slots, and cushioning means between the upper ends of said slots and said journal boxes.

8. A truck-frame as set forth in claim 5 further characterized by at least two sets 105 of journal box slots at the rear end portion of said frame to interchangeably receive the journal boxes of said rear axle, one set of journal box slots being positioned in advance of the tractor rear axle support and the other set being positioned to the rear thereof.

9. A truck-frame as set forth in claim 5 further characterized by at least two sets of journal box slots at the rear end portion of 115 said frame to interchangeably receive the journal boxes of said rear axle, one set of journal box slots being positioned in advance of the tractor rear axle support and the other set being positioned to the rear thereof, each set being equally spaced on opposite sides of the supporting bracket for the tractor rear axle, said rear traction wheels of the truck frame having a gear fast thereto, and a gear for each end of the tractor rear axle to mesh with the gear on said traction wheels of said truck frame, when the tractor is mounted in position on said truck frame, irrespective of the position of 120 the rear axle.

10. A truck-frame for converting tractors into locomotives comprising side plate members connected at their ends by transverse end members, front and rear traction wheels for said truck-frame journaled on the latter, means for supporting a tractor in position on said frame comprising a transverse vertical plate having its end members laterally extended and secured to said side plates and having an aperture therein at a medial point in its length below its upper edge, whereby the front coupling of the tractor may be secured to said plate by a trunnion pin extending through the opening in said plate, said means further comprising a pair of bracket plates one secured to the rear end portion of each side plate members of the frame, said bracket plates having their upper edges formed to receive the ends of the rear axle housing of the tractor and each having a lateral perforated flange thereon, U-bolts to extend around said axle housing of the tractor and through said perforations in said flange, means for securing said bolts in position, and a driving connection whereby the traction wheels of the frame may be driven from the rear axle of said tractor.

11. A truck-frame as set forth in claim 10 further characterized by said transverse end members of the frame having their ends extended laterally thereto and secured to the ends of said side plate members, and horizontal bracing plates or webs, one between the lateral ends of each end member, said plates or webs forming transverse braces and extending inwardly of the frame.

12. A truck-frame for converging tractors into locomotives comprising side plate members connected at their ends by transverse end members, front and rear traction wheels for said truck-frame journaled on the latter, a transverse brace between the front end portions of said side members for supporting the front end of said tractor, and a pair of brackets, one on each of said side plates for supporting the rear end of said tractor, each of said brackets comprising a plate having a recessed upper edge to receive an end of the rear axle housing of the tractor, a lateral flange on each of said plates having perforations therein, and U-bolts associated with each of said brackets to extend around the end of said axle housing and through the perforations in said flanges, and means for securing said bolts to said flanges.

13. In a sub-frame for tractors, a supporting frame including vertical side plate members permitting flexure thereof transversely of the frame and connected at their ends by transverse members, front and rear traction wheels for the frame journaled on the latter, means for supporting a tractor in position on the frame including a transverse cradle-like brace having its ends se-

cured to said side plate members and adapted to support the front end of a tractor, said tractor supporting means further including supporting brackets on each of said side plate members of the frame for the rear axle of the tractor, and driving connection whereby the traction wheels of the frame may be driven from the rear axle of said tractor.

14. In a locomotive of the character described, a truck frame, traction wheels on said truck frame, propelling mechanism on said frame connected with said traction wheels, and upwardly extending plates on the ends of said truck-frame, each of said plates being coextensive with the width of the frame and extending upwardly therefrom for a distance to shield the motor from shifting loads from cars to which the locomotive may be attached, said plates being perforated to permit air to pass therethrough to the propelling means and reduce the air pressure thereagainst when the locomotive is moving.

15. In a sub-frame for tractors comprising side plate members connected at their ends by transverse members, the lower edge of said plate members being provided at their front and rear portions with vertically extending slots, journal boxes mounted in said slots, transverse axles mounted in said journal boxes, traction wheels on said axles, means on the frame for supporting a tractor thereon, means for establishing a driving connection between the tractor and, at least, one of the traction wheels of the frame.

16. A truck-frame for converting tractors into locomotives comprising a frame, supporting brackets at the front and rear portions of the frame for detachably receiving and supporting the tractor thereon, front and rear axles on the frame and having traction wheels thereon, means on the frame positioned in advance of said rear supporting brackets for maintaining said rear axle on the frame, means on the frame positioned to the rear of said rear supporting brackets for interchangeably receiving said rear axle and maintaining it on the frame, and means whereby said rear traction wheels may be driven from the rear axle of the tractor when mounted in said rear brackets, in either position of said rear axle.

17. A truck frame including side members, spaced axles mounted in bearings on the frame, said side members of the frame permitting flexure thereof throughout its length transversely of the frame, and wheels for the axles.

18. A truck frame including side members, spaced axles mounted in bearings on the frame, said side members comprising intermediate plate-like portions between

said axles capable of flexing throughout therebetween, whereby the frame may flex transversely under strain.

19. A truck frame comprising side members, spaced axles mounted in bearings on said side members and spaced from the ends thereof, wheels for said axles, said side members permitting flexure thereof transversely of the frame, means for supporting

the load on the frame, said means being positioned at a point between the ends of the frame and said axles to prevent the buckling of the frame due to flexure.

In testimony whereof we have hereunto set our hands.

HENRY E. RESTER.

GEORGE BOYLE WERCKLEY.
